[57] **CLAIM**

The ornamental design for a building block, as shown and described.

DESCRIPTION

FIG. 1 is a perspective view of a building block showing my new design;

FIG. 2 is an end elevational view thereof;

FIG. 3 is a front elevational view thereof, it being noted that the rear elevational view is identical to the front elevational view in appearance;

FIG. 4 is a bottom plan view thereof.

FIG. 1

FIG. 2

FIG. 3

FIG. 4
